UNITED STATES PATENT OFFICE.

GEORGE SEEL, OF OAK HILL, OHIO.

PLATE-LIFTER.

990,913.

Specification of Letters Patent.

Patented May 2, 1911.

Application filed January 27, 1911. Serial No. 605,101.

To all whom it may concern:

Be it known that I, GEORGE SEEL, a citizen of the United States, residing at Oak Hill, in the county of Jackson and State of Ohio, have invented certain new and useful Improvements in Plate-Lifters; and I do hereby declare the following to be a full, clear, and exact description of the invention, such as will enable others skilled in the art 5 to which it appertains to make and use the same, reference being had to the accompanying drawings, and to the letters and figures of reference marked thereon, which form a part of this specification.

15 This invention relates to new and useful improvements in plate holders and devices for lifting hot dishes, lids, etc., and comprises a simple and efficient device of this nature having various details of construction and combinations and arrangements of parts which will be hereinafter fully described and then specifically defined in the appended claim.

I illustrate my invention in the accompanying drawings, in which:—

Figure 1 is a perspective view showing the application of my invention, and Fig. 2 is a view showing the device folded.

Reference now being had to the details 30 of the drawings by letter, A designates a wire which has two parallel arms B and B', each of which terminates at the end of a bail-shaped portion C in a plane at right angles to the two parallel parts, forming 35 means for engagement over the edge of a plate or dish. Said arm B is bent to form an eye F and thence has a laterally extending part G engaging one of the eyes H and I formed near the end of the arm B'. A 40 second wire, designated by letter N, is bent upon itself and twisted together forming, with the rearwardly returned parallel portions N', a handle, the ends of which wire N are bent to form eyes O through which 45 arms of the wire pass, as shown, and bent in substantially rectangular shape with portions pivotally connected to the eyes H and

F and said wire, after being bent to form said rectangular portion, has portions Q bent parallel to each other and thence at 50 right angles, forming a terminal member R which is adapted to engage over the plate at locations diametrically opposite that engaged by the first referred to member.

In operation, the bail-shaped member C 55 is caught over the edge of the plate to be lifted and the other bail-shaped member adjusted to the other edge of the plate, it being noted that the device is adapted to fit plates of different diameters and, by lifting 60 upon the handle, the dish or plate may be raised.

In order to reinforce and hold the bail-shaped member C rigid, the parallel portions Q bear frictionally against the cross-piece G and which will serve to hold the arms B and B' substantially in a line with the sides of the wire N, thus securely holding the dish or plate while being lifted.

When not in use, the parts may be folded 70 back upon themselves as shown.

What I claim to be new is:—

A folding plate lifter comprising two wires, one of which is bent to form a bail-shaped hook to engage over the edge of a 75 plate and provided with parallel shank portions, the end of one of which has formed therein two eyes, the other shank portion bent to form a single eye, thence bent at right angles to engage one of the eyes in the 80 opposite parallel portion, a second wire bent to form a substantially rectangular outlined portion pivotally mounted in two of said eyes and provided with a handle, one side of said rectangular outlined portion bent to 85 form a terminal member for engagement with the edge of the plate.

In testimony whereof I hereunto affix my signature in the presence of two witnesses.

GEORGE SEEL.
